H. PETER.

CARBURETER FOR INTERNAL COMBUSTION ENGINES.

APPLICATION FILED JULY 13, 1916.

1,271,610.

Patented July 9, 1918.

INVENTOR:

HANS PETER

By: *Hans Peter*
ATTORNEY.

UNITED STATES PATENT OFFICE.

HANS PETER, OF Liestal, Switzerland.

CARBURETER FOR INTERNAL-COMBUSTION ENGINES.

1,271,610.

Specification of Letters Patent.

Patented July 9, 1918.

Application filed July 13, 1916. Serial No. 109,017.

To all whom it may concern:

Be it known that I, HANS PETER, a citizen of the Swiss Republic, and resident of Lies-
tal, in the Republic of Switzerland, have
5 invented new and useful Improvements in
Carbureters for Internal-Combustion En-
gines, of which the following is a full, clear,
and exact specification.

This invention relates to a carbureter for
10 internal combustion engines and to that class
of devices wherein the liquid fuel is supplied
by capillary passages and drawn in by means
of the air supplied for combustion.

According to the invention the finest pul-
15 verization of the liquid fuel by means of the
air current in the induction passage is ef-
fected through the medium of a bundle of
separate elastic, flexible threads, not a wick,
which threads are loosely outstanding at
20 the discharge end and are set into vibration
by the air current at the end at which the
liquid is picked off, whereby the liquid
threads are by a whip or lash-like action pul-
verized to a fine mist and delivered to the
25 air.

The accompanying drawing shows in sec-
tional elevation one form of carbureter em-
bodying the principle of the invention.

In the construction illustrated, *a* is a tube
30 the upper end of which is directly attached
to the induction connection of a motor cyl-
inder and which is provided at its upper
part with a suction-nozzle *b*. Up to the
lower orifice of this nozzle there extends a
35 thread bundle *d* having capillary passages
between its threads and the lower extremity
of which dips into a liquid fuel containing
compartment of a socket *e* held within a
liquid fuel receptacle *e'*. The combustible
40 liquid is supplied to the latter through the
lateral inlet *f* from a vessel furnished with
a float-feed, and not shown in the drawing,
so that the level of the liquid remains con-
stant in the socket *e*. The air necessary for
45 the formation of the combustible mixture
enters the tube *a* at its lower end and is
drawn in a strong current over the upper
end of the thread bundle *d* from which it
picks off the liquid which issues from the
50 capillary passages of said bundle and which
has been subdivided into extremely fine
threads by the practically parallel, continu-
ous capillary passages which extend between
the threads of the bundle *d*, the thus pul-

verized liquid fuel mixing with the air cur-
rent in the nozzle *b*, and further liquid ris-
ing in the capillary passages of the bundle *d*.

The liquid fuel feeding bundle *d* is com-
posed of a large number of separate, elastic,
flexible threads, such, for example, as horse-
hair, which is inserted in the sleeve-like part
of the socket *e* and the upper end of which
projects freely outstanding and is expanded
60 to a conical shape by a spraying cone *m*.
The upper free extremities of the threads
of the bundle, which are spread out elas-
tically to an oblique position, are vibrated
by the air current striking externally upon
65 them and by their whip or lash-like action
thus set up, pulverize the liquid which has
risen through the capillary passages pro-
vided between the threads of the bundle and
discharge the thus pulverized fluid into the
70 air. As will be seen, the arrangement is one
which provides at the discharge end of the
bundle *d* a spreading of the liquid which
is favorable to its distribution.

The above described device is suitable for
use with light and heavy hydrocarbons and
in all cases a complete, soot-free combustion
80 is obtained. This may be due mainly to
the extremely fine pulverization of the com-
bustible at the discharge end of the thread
bundle *d*.

What I claim is:

1. In a carbureter for internal combus-
tion engines, an air induction tube, a liquid
fuel container combined therewith and a
liquid fuel feeding bundle of separate, elas-
tic, flexible threads, said bundle being so ar-
ranged as to have its lower end within said
liquid fuel container and its upper end freely
projecting into said air induction tube, so
that the induced air current may cause the
90 free upper ends of the threads to vibrate
and to thus pulverize the fuel by a whip-like
action to fine mist delivered to the air, sub-
stantially as hereinbefore described.

2. In a carbureter for internal combustion
engines, an air induction tube, a liquid fuel
container combined therewith and a liquid
fuel feeding bundle of separate, elastic, flexi-
ble threads, said bundle being so arranged
as to have its lower end within said liquid
fuel container and its upper end freely pro-
jecting into said air induction tube, in com-
bination with a sprayer arranged to expand
100 or spray out said upper bundle end to a
105

freely outstanding position, so that the induced air current may cause the free upper ends of the threads to vibrate and to thus pulverize the fuel by a whip-like action to fine mist delivered to the air, substantially as hereinbefore described.

In witness whereof I have hereunto signed

my name this 23rd day of June 1916, in the presence of two subscribing witnesses.

HANS PETER.

Witnesses:

ARNOLD ZUBER,
AMAND BRAUN.
